UNITED STATES PATENT OFFICE.

WILLIAM J. HOSCEIT, OF CHICAGO, ILLINOIS, ASSIGNOR TO RODGER BALLAST CAR COMPANY, OF CHICAGO, ILLINOIS, A CORPORATION OF MAINE.

CONTROLLED-DISCHARGE DUMP CAR.

Application filed July 26, 1926. Serial No. 124,966.

This invention relates to dump cars of the kind in which the cargo, when discharged, is deposited in definite relation to the track or right of way, for instance, within more 5 or less defined limits between the rails and on either side thereof.

The object of the invention is to provide means through which to effect a more exact control of the discharge and a better defined 10 limitation, in directions transverse to the right of way, of the piles of material deposited, thereby avoiding waste of material which might otherwise pass beyond the area requiring the material, or unnecessary labor 15 in bringing the material back to where it is needed.

It has heretofore been proposed to provide a hopper bottom dump car with a door or doors independently controllable, adapted to 20 assume positions from which, when the doors are open, they will direct the material to either the space between the rails of a railway track, or the outer sides of the rails; but in dump cars of this kind as heretofore constructed, owing to the force with 25 which the material issues over the opened door or doors, and particularly between the time of initial opening and the time the door reaches full open position, during 30 which its angle of elevation is too great to properly direct the material, a considerable portion of the cargo is deposited too far from the point desired. The present invention avoids this objection by providing, at 35 the discharge opening and in cooperative relationship to the door, a baffling apron which restricts flow of material over the door at the time of discharge by assuming a position at a substantial angle to the direction of flow, and at a distance from the 40 door which will enable it to reduce the vertical dimension of the stream of material; such baffling apron or baffle being movably mounted, as, for instance, by hinging it upon an axis parallel with that upon which 45 the door swings, and has its axis of movement so related to that of the door that commencing with the beginning of opening movement of the door and continuing until 50 such time as the door shall have reached a predetermined angle of elevation at which it exercises proper control over the material, the baffle will meet and remain in a relation of meeting or approximate meeting with the 55 door, thereby preventing escape of material

so long as the door is at an angle which is undesirable for directing the material, and preferably when the door has reached full opening position, will still remain as a controlling factor in the discharge by regulating the vertical dimension of the stream of material by the distance of the baffle from the door.

In accordance with subordinate features of the invention incident to the broad principles above outlined, the baffling apron or baffle has its axis of pivotal action located in or at such proximity to the plane of the door when closed that it will overlie the door, so that it will have the advantage of 60 being sustained by the door elevating and securing means, through the medium of the door upon which the swinging end of the baffle rests, as well as the advantage of remaining in supported relation to the door, 65 in resisting escape of the cargo throughout the fore part of the door's opening movement.

The invention applies to doors opening toward the middle of the track as well as 70 those opening toward the sides.

The accompanying drawing, in which the invention is illustrated more or less schematically, represents a vertical transverse section through the lower portion of a 75 known design of selective dump car for transportation of subdivided material in bulk, and shows the preferred embodiment of the invention incorporated therein by way of illustration.

1 represents the center sill of a car, 2 the side walls of the hopper bottom thereof, and 3 and 4 are, respectively, side and middle discharge doors pivotally mounted upon a common horizontal axis 5 extending longitudinally of the car and adapted to assume either the closed positions illustrated at the right side of the figure, to which they may be moved by any approved form of closing means, such, for instance, as flexible connections 6, 7, leading from manually or otherwise controlled winding drums 8, 9, over pulleys 10, 11 to the side doors 3 and 4, or adapted to assume, under the force of gravity, the open positions shown at the left-hand side of the figure, when their elevating connections and any locking or securing means with which they may be provided are released. Mounted upon fixed portions of the car structure, for instance, through the 100

medium of hinges 12 and 13, adjacent the swinging ends of the doors when in closed position, are baffles 14 and 15 in the form of aprons which, when the doors are closed, 5 overlie and have their free ends supported by the doors, as shown at the right-hand side of the figure, but which, when the doors are opened, drop to substantially vertical or other predetermined position, as shown at 10 the left-hand side of the figure, and in which latter position the baffles are adapted to materially restrict and retard the flow of material from the car and prevent it cascading to a point beyond the area in which it is 15 needed. More than this, the baffles 14 and 15, by means of the relation of their free ends to the doors through a large part of the arc of opening movement of the doors, during which their said free ends are in 20 meeting or substantial meeting with the surfaces of the doors, will delay the time at which discharge commences, until the directing angle of the door is approximately that selected to effect the form of delivery desired. In other words, one important feature of the baffle control is that resulting 25 from its influence over the stream of material after the door reaches its predetermined inclination of full open position. Another 30 important feature is that which arises from obstruction of cargo during the fore part of the opening movement of the door.

While the invention has been described in connection with both of two different doors 35 discharging, respectively, inwardly and outwardly relatively to the track, and the doors selected for illustration are mounted upon axes extending longitudinally of the car, the invention is applicable to single doors in 40 various positions; nor is it limited to the specific relation of the baffle to the door, or the particular construction of baffle shown.

Any suitable means may be employed for 45 swinging the baffles 14 and 15 toward closing position sufficiently in advance of the upward swinging of the doors 3 and 4, or until the baffles are at such angles as will enable the doors to assume control of their closing movements. For instance, the flexible 50 connectors 6 and 7 may be passed from the guide sheaves or pulleys 10 and 11, not directly to the doors 3 and 4, but indirectly by way of guide sheaves or other deflecting surfaces 16 and 17, mounted at the sides of 55 the baffles at points which, when the doors and baffles are in closed position, will substantially coincide with the points 18, 19 at which the flexible connectors meet the doors, the effect being to permit the parts to 60 assume positions shown at the left-hand side of the figure when the elevating means are fully released, but by the tendency of the connectors to conform to a straight line under tension when wound upon drums 8 and 9, first to draw the baffles 14 inward to

a point where they will readily deflect upward under pressure of the door (which point can readily be gauged by the offset of the guide points 16 and 17 from the planes of the baffles) and thereafter be 70 moved to fully closed position in which they overlie the doors, as at the right-hand side of the figure, under the full closing movement of the doors.

I claim:

1. In a dump car, a door controlling discharge from said car, and a baffle movable with said door, restricting flow of material in such discharge; said baffle being presented at a substantial angle to the direction of discharge, and regulating the discharge by its distance from the door. 75

2. In a dump car, a door controlling discharge from said car, and a baffle restricting flow of material in such discharge; said baffle being movable with and at the opening of the door, from a position in which it intercepts the material, to a position in which it is spaced from the door and permits discharge of the material. 85

3. In a dump car, a door controlling discharge from said car, and a baffle restricting flow of material in such discharge; said baffle being movable with and at the opening of the door, from a position in which it 95 meets the door and intercepts the material, to a position in which it is spaced from the door and permits discharge of the material.

4. In a dump car, a door controlling discharge from said car, and a baffle restricting flow of material in such discharge; said baffle being movable with and at the opening of the door, from a position in which it meets the door and intercepts the material to be discharged, to a position in a plane 105 which intersects the direction of flow, but spaced from the door in said plane and defining, with the door, a vertically restricted channel of flow. 100

5. In a dump car, a door controlling the 110 discharge of material therefrom, a baffle movably mounted on said car, overlying the door in the closed position of the door, and moving, at the opening of the door, to a position restricting flow of material past the 115 door.

6. In a dump car, a swinging door controlling discharge from said car, and a baffle mounted on the car in position to lie parallel with the door when the door is 120 closed, and movable at the opening of the door to a position at a substantial angle to the door and spaced therefrom to define, with the door, a restricted channel of discharge. 125

7. In a dump car, a swinging door controlling discharge from said car, and a baffle mounted on the car in position to lie parallel with the door when the door is closed, and movable at the opening of the door to a po- 130

- sition at a substantial angle to the door and spaced therefrom to define, with the door, a restricted channel of discharge; the baffle remaining in meeting relation to the door and totally arresting flow of material during the fore part of the opening movement of the door.
8. In a dump car, a door controlling the discharge of material from said car and moving from closed position to a position in which it permits discharge of material and determines the direction of flow, and a baffle movable from a position of meeting with the door, in which it arrests the flow of material to a position of removal from the door in which, by the distance of such removal, the baffle and the door define a channel of discharge for said material.
9. In a dump car, a discharge opening, a door for determining the size of said opening swinging from a position closing said opening to a position of maximum opening in which it provides the bottom of a channel of discharge, and a baffle swinging about an axis remote from the axis upon which the door swings, and having a path of movement which causes the free end of the baffle to meet the door and obstruct flow of material thereover during the fore part of the movement of the baffle, and thereafter assume a position spaced from the door and permit flow of material.
10. In a dump car, a discharge opening, a door for determining said opening from a completely closed to a completely opened position of said door swinging upon a horizontal axis to release material from said car, a baffle pivoted upon an axis remote from the axis of the door but permitting the free end of the baffle to rest upon the door when the door is in closed position, and giving to the baffle a path of movement which keeps the baffle in meeting with the door during a part of the opening movement of the door, and thereafter removes the free end of the baffle from the door to permit material to escape over the door.
11. In a dump car having a hopper bottom discharge and a door for controlling the escape of material therefrom, a baffle movable through a path which causes it to substantially intersect the path of discharge of material during a portion of its movement, and thereafter assume a position removed from said path of discharge.
12. In a hopper car, a door permitting discharge therefrom, a baffle controlling such discharge, having a path of movement which causes it to be engaged by the door, and means for moving the baffle to a position in which the door assumes control of the baffle.
13. In a dump car, a discharge opening, a door for determining the size of said opening from a completely closed to a completely open condition, and a baffle restricting flow of material through said discharge opening.
14. In a dump car, a discharge opening, a door for determining the size of said opening from a completely closed to a completely open condition, and a baffle restricting flow of material through said discharge opening, said baffle being presented at a substantial angle to the direction of discharge, and regulating the discharge by its distance from the door.
15. In a dump car, a discharge opening, a door for determining the size of said opening from a completely closed to a completely open condition, and a baffle restricting flow of material through said discharge opening, said baffle being movable, at the opening of the door, from a position in which it intercepts the material, to a position in which it is spaced from the door and permits discharge of the material.
16. In a dump car, a discharge opening, a door for determining the size of said opening from a completely closed to a completely open condition, and a baffle restricting flow of material through said discharge opening, said baffle being movable, at the opening of the door, from a position in which it meets the door and intercepts the material, to a position in which it is spaced from the door and permits discharge of the material.
17. In a dump car, a discharge opening, a door for determining the size of said opening from a completely closed to a completely open condition, and a baffle restricting flow of material through said discharge opening, said baffle being movable, at the opening of the door, from a position in which it meets the door and intercepts the material to be discharged, to a position in a plane which intersects the direction of flow, but spaced from the door in said plane and defining, with the door, a vertically restricted channel of flow.
18. In a dump car, a controlled discharge, comprising a door the position of which determines the flow of material from said car from completely shut off to a maximum flow, and means cooperating with said door for restricting the opening provided by said door in certain predetermined positions of said door.
19. In a dump car, a car floor having an opening therein, a door for closing said opening and for determining by its position the size of the discharge outlet for said car, means cooperating with said door for restricting the opening provided by said door in certain predetermined positions of said door.

Signed at Chicago, Illinois, this 20th day of July, 1926.
